UNITED STATES PATENT OFFICE

EMIL SCHÜNEMANN, OF HAMBURG, GERMANY

DEVICE FOR INCREASING THE WATER CIRCULATION AND FOR DECREASING BOILER RESISTANCES TO FLOW IN CENTRAL HEATING PLANTS

Application filed June 17, 1929, Serial No. 371,605, and in Germany June 25, 1928.

It is a well-known fact that, in order to effect the quick approximation of the temperatures in the descending and ascending pipes in central heating plants, there must be a rapid circulation of water through the plant. For this reason attempts have already been made, in the case of large plants, for instance to interpose pumps, but the results obtained in this way have not been satisfactory. Quite apart from this, it must be borne in mind that such pumps, if installed in plants of small or medium size, would be too costly and would occupy too much space.

The present invention starts from the knowledge that the two obstructions to a sufficiently quick circulation of the water are first, the insufficiently high temperature in the ascending pipe, and second, considerable resistances to flow in the boilers. These resistances are especially large in the case of the much used sectional boilers, the various sections of which are connected by means of nipples; and it is generally known that, owing to the reduction of the cross sections due to nipple connections, the water leaving the reflow distributes itself so that more water flows through in the first few sections than in the others.

In order to raise the temperature in the ascending pipe and to diminish the boiler resistances, the invention provides for the installation of a water heating coil in the boiler and of one or more distributor pipes in connection with the pipes feeding the boiler and withdrawing water from it. Whereas the former installation causes the temperature in the ascending pipe to rise, the distributor pipes are intended to replace the different contractions of the cross sections by a uniform through-flow section.

One end of the coil is connected to the distributor pipe of the re-flow, whereas the other end, after the manner of an injector, is joined to the ascending pipe, which, in its turn, is connected with the distributor pipes in the fore-flow.

The special effect of thus connecting the water heating coil and the distributor pipes is that the re-flow of the coil brings about a suction effect in the pipe installed in the re-

flow of the boiler, so that part of the water from the re-flow pipes is drawn through the re-flow of the boiler, thus ensuring that uniform quantities of water are conveyed to the various sections of the boiler.

For this reason the openings in the distributor pipe of the re-flow through which the water enters the boiler sections are arranged side by side to one another at an angle to the horizontal plane. More particularly, the openings admitting water to the front sections are arranged underneath the horizontal middle-line, and those up to the last section are made to rise slantingly to the horizontal middle-line of the pipe, i. e., somewhat after the manner of a spiral. In the fore-flow, on the other hand, all the openings are arranged in the horizontal middle-line of the distributor pipe.

In the accompanying drawings the object of the invention is shown as adapted to a concrete case. The various figures show:

Fig. 1—longitudinal section of the invention as installed in a sectional boiler.

Fig. 2—cross section of the same.

The water heating coil (a) is somewhat semi-circular in shape and has been adapted, in its shape, to that of the furnace (b) of the sectional boiler. (Cf. Fig. 2). One end of the coil has been suitably introduced, after the manner of an injector, into the fore-flow of the plant (c), this being effected by means of the pipe (1). The other end of the coil is joined, by means of the pipe (d), to the distributor pipe (g), said pipe being situated at the opposite end of the water admission to the boiler, i. e., opposite to the re-flow pipe of the plant (e). The distributor pipe (g) is provided with the openings (h) on the side of the boiler sections. These openings are located, as may be seen from Figure 1, below the middle-line of the pipe as far as the first few sections are concerned, but they rise up to the level of the middle-line in the case of the succeeding sections. This mode of arranging the openings ensures that

the water leaves the pipe (g) and enters the boiler sections in a uniform manner and without the formation of any eddies. It is advisable to connect the pipe (d) to the dis-

tributor pipe (g) in nozzle-like fashion by means of the cone (n), so that the water is enabled to flow to the last boiler section in a uniform manner and without any eddies.

5 The water which now rises uniformly in the sections, flows uniformly into the upper distributor pipe (i) of the boiler pipe. There the admission openings (k) are located on the side of the pipe, symmetrical to the middle-lines of the latter.

10 A connection (o) may be made to branch off from the pre-flow (l) of the water heating coil (a) to a boiler. In this way it will be possible to feed another boiler for a time, 15 a matter which until now, owing to the low temperature in the fore-flow (about 45 or 50 degrees), was not possible by means of one boiler only.

Such branching-off makes it also possible 20 to convey the admission pipe and the suction pipe—in the case of heating plants not functioning satisfactorily—to that part of a plant which functions unsatisfactorily. In this way the circulating effect of the water-heating coil may be directed to different parts 25 of the plant to increase the heat at such part and thereby induce a more ready circulation.

In order to prevent the coil from being 30 completely turned off in the event of the valve concerned being inadvertently adjusted the wrong way, a permanent through-flow opening of small cross section has been provided for valve (p).

What I claim to be new is:

35 1. A device for increasing the water circulation and tending to equalize the return flow within a boiler, comprising a distributor pipe receiving the return flow of the water and delivering it at a plurality of points 40 within the boiler, an outlet pipe for delivering hot water from the boiler, and a water heating coil having the inlet end in communication with the distributor pipe to thereby create a suction on the water flowing through 45 said pipe, the outlet end of the coil connected to the outlet pipe for delivering the flow from the coil into the heated water flowing from the boiler at a point beyond the boiler.

50 2. A device for use in central heating plants and serving to increase the water circulation and decrease the boiler resistance to return flow, comprising a distributor pipe arranged within the boiler and receiving the return flow, said distributor pipe being 55 formed with a plurality of openings for delivering the water of the return flow at spaced points in the boiler, an outlet pipe for the delivery of hot water from the boiler, a water heating coil having the inlet end in communication with the distributor pipe to thereby create a suction in said pipe and having its outlet connected to said boiler outlet pipe.

55 3. A heating plant including a boiler, an outflow pipe therefrom, an inflow pipe there-

to, a distributor pipe connected with the inflow pipe and arranged within the boiler, said distributor pipe being formed with a plurality of openings to deliver the inflow of water at spaced points in the boiler, and a 70 water heating coil having its inlet end connected with the distributor pipe at a point remote from the connection of the latter and the inflow pipe, the outlet of the coil being connected with the outflow pipe from the 75 boiler at a point beyond the boiler.

4. A heating plant including a boiler, an outflow pipe therefrom, an inflow pipe there- 80 to, a distributor pipe connected with the inflow pipe and arranged within the boiler, said distributor pipe being formed with a plurality of openings to deliver the inflow of water at spaced points in the boiler, and a water heating coil having its inlet end connected with the distributor pipe at a point 85 remote from the connection of the latter and the inflow pipe, the outlet of the coil being connected with the outflow pipe from the boiler at a point beyond the boiler, the openings in the distributor pipe being arranged 90 at decreasing angles to the direction of flow of the water in said boiler in order to present successively decreasing resistance to the outflow of water therefrom from the point of connection of the distributor pipe to the in- 95 flow pipe.

5. In a boiler heating plant, a distributor pipe arranged within the boiler and receiving the inflow to the boiler, said pipe being 100 formed with a plurality of outlets for delivering the inflow of water at spaced points in the boiler, an outflow pipe for said boiler, a water heating coil, a suction nozzle forming the inlet to the coil and arranged in communication with the distributor pipe, and an 105 injector at the outflow end of the coil leading into the outflow pipe of the boiler at a point beyond the boiler.

6. A heating plant including a boiler, an outflow pipe therefrom, an inflow pipe there- 110 to, a distributor pipe connected with the inflow pipe and arranged within the boiler, said distributor pipe being formed with a plurality of openings to deliver the inflow of water at spaced points in the boiler, a super- 115 heater coil having its inlet end connected with the distributor pipe at a point remote from the connection of the latter and the inflow pipe, the outflow pipe of the coil being connected with the outflow pipe from the 120 boiler at a point beyond the boiler, and a lead from the outflow pipe of the superheater coil whereby the effect of the superheater coil may be distributed to other parts of the system.

125 In testimony whereof I affix my signature.

EMIL SCHÜNEMANN.
